UNITED STATES PATENT OFFICE

ISAAC MARINSKY, OF PROVIDENCE, RHODE ISLAND

COLLAR STIFFENER DEVICE

Application filed July 6, 1931. Serial No. 548,789.

My invention relates to men's shirts and more particularly to the soft turn down shirt collars thereof either attached or detached and to stiffening elements therefor.

5 The essential objects of my invention are to retain the collar ends or points in contact with the shirt front or bosom; to prevent wrinkling or curling of the collar points; to maintain the collar smooth and relatively 10 stiff under all circumstances; to provide a locking stiffening element adapted to facilitate removal but safe from accidental escape, and thoroughly concealed from observation; and to attain these ends by simple, inexpensive, and easily operable means.

To the above ends essentially my invention consists in such parts and in such combinations of parts as fall within the scope of the appended claims.

20 In the accompanying drawings which form a part of this specification,

Figure 1 is a fragmentary front elevation of a shirt of the attached collar type with one of the collar points turned up and its stiffening strip member removed.

Figure 2, a section of the same on line 2—2 of Figure 1,

Figure 3, a fragmentary rear view of a portion of the shirt front disclosing the back 30 of the pocket therein.

Figure 4, a perspective view of the stiffener member taken from the front,

Figure 5, a section of a modified form of one of the shirt pockets taken on a line corresponding with line 2—2 of Figure 1, and

Figure 6, a fragmentary front elevation of a shirt, detachable shirt collar, and a stiffener element.

40 Like reference characters indicate like parts throughout the views.

As herein illustrated 10 represents the front or bosom of an ordinary soft shirt, 11 the attached collar band, and 12 the flap of 45 the soft or semi soft shirt collar 13. The flap is provided with points 15. A triangular strip 18 is bound to the under face of each point by lines of stitches 21 on the bottom and end edges of the collar or otherwise. The 50 strip forms a triangular upwardly directed

pocket 22 having a horizontal mouth 23 at its top.

In the upper portion of the shirt behind each point is a downwardly directed pocket 26 extending from a point at or adjacent the collar band 11 to a horizontally disposed slit 28 in the shirt bosom forming the mouth of the pocket.

A convenient or preferred method of forming the pocket 26 is to manually hold a vertically disposed strip of tape against the back of the shirt bosom, and centrally of the strip slit an opening 28 simultaneously through both the bosom 10 and the strip, and then sew the last mentioned parts together with button hole stitching 29 around the slit or opening. The length of tape is next folded together and upwardly directed forming a back and a front wall 31 and 32 bound to each other at their sides and with the shirt front by stitches 35, and bound at their upper ends to the shirt by a line of stitching 38, and in this case, also by the collar band stitching 39. By virtue of the double walls 31 and 32 the portion 40 of the bosom 10 overlaying the pocket is protected by the wall 32, and that the wall 31 protects the contents of the pocket from contact with the wearer's body. The mouth 28 of the shirt pocket is in vertical alignment with and above the mouth 23 of the collar pocket.

In Figure 5 a modified form of the shirt pocket is shown which differs from the above described structure in omitting the front pocket wall 32.

Two longitudinally convexo concave stiffener strip members 42 of thin sheet metal, celluloid, or other flexible or resilient material, comprise each a substantially triangular head portion 43 and a shank portion 44. Each stiffener member has its shank 44 and head 45 slidably inserted in one of the shirt pockets and one of the adjacent collar pockets respectively. The maximum width of the head portion 43 is greater than the width of the slit 28 and pocket 26.

The triangular form of head accommodates itself in its triangular pocket and thus assists to keep the collar point transversely distended at the portion most susceptible to

distortion or displacement. The slightly convex shape of the stiffener member tends to direct the point of the collar toward the shirt bosom rather than away from it. The flexible character of the member 42 facilitates the insertion and removal thereof from the pocket and assists to maintain a vertical tension upon the collar flap or point.

In Figure 6 the binding 46 of the shirt collar is shown additionally to the shirt collar binding 47, as is common when separable rather than integral shirt collars are employed.

I do not desire to be understood as confining myself to the specific construction of the parts shown, and such changes or modifications may be made in practice as fairly fall within the scope of my invention as claimed.

I claim:

1. The combination of a shirt provided with a horizontal slit, a turn down collar upon the shirt provided with a vertical pocket in the turn down part of the collar, and a stiffener strip member seated in the pocket, and extending through the slit.

2. The combination of a shirt provided with a pocket, a turn down collar carried by the shirt overlapping the pocket and provided with a pocket in its turn down part, and a stiffener strip member in the pockets.

3. The combination of a shirt provided with a pocket, a collar upon the shirt including a turn down part overlapping the pocket and provided with a pocket below the first pocket and a resilient stiffener strip member seated in the pockets.

4. The combination of a shirt provided with a pocket, a turn down collar carried by the shirt including a point in its turn down part and provided with a pocket in said turned down part in vertical alignment with the first pocket, and a detachable flexible stiffener strip member comprising a shank in the first pocket and a head in the second pocket.

5. The combination of a shirt provided with a horizontally disposed slit, a turn down collar upon the shirt having its turn down part overlapping the slit and provided with a vertical pocket in the turn down part, and a detachable stiffener strip member comprising a head in the pocket of greater maximum width than the slit, and a shank extending through the slit.

6. The combination of a shirt provided with a pocket, a turn down collar upon the shirt overlapping the pocket and provided in its turn down part with a pocket below the first pocket and in vertical alignment therewith, and a flexible convexo concave stiffener strip member in the pockets.

7. The combination of a shirt provided with a horizontally disposed pocket slit, vertically disposed pocket walls fixed to the shirt and registering with the slit, a turn down col-

lar upon the shirt overlapping the slit and provided in its turn down part with a pocket in vertical alignment with the slit, and a stiffener member in the pocket in the collar and extending through the slit and between the pocket walls.

In testimony whereof I have affixed my signature.

ISAAC MARINSKY.
